Peter De Mattia, Passaic, N. J.

Application February 11, 1941, Serial No. 378,388

22 Claims. (Cl. 74—106)

This invention relates to toggles and similar devices.

One object of the invention is to provide a device comprising a plurality of links constructed in an improved manner for direct pivotal abutment between the links to avoid shearing strain on pins, especially in or near dead center position.

Another object of the invention is to provide a device comprising spaced relatively movable members, and means comprising links interengaged for direct abutment with each other and with at least one of the members in an improved manner to avoid pin shearing stresses.

Another object of the invention is to furnish a device as set forth having improved means for direct abutment along surfaces rolling on each other in course of pivotal movement.

Another object of the invention is the provision of a device comprising a toggle having a pivotal link arranged or constructed in an improved manner to exert an abutting pressure throughout a plane surface area for maximum resistance against a compression load.

Another object of the invention is to furnish a device as referred to having improved pivotally interengaged elements directly abutting in rolling interengagement coaxially with connecting bearings in which the pivotal movement is limited, whereby the device is easily controlled if one of the elements has a temporarily free end.

Another object of the invention is to provide a device including a linkage one end of which is desirably connected to a movable member and the other end of which is movable into and out of engagement with a fixed member, at least part of the linkage being operable to initially move the movable member and the linkage being then engaged with the fixed member for final movement of the linkage to dead center position, whereby compactness is increased, and the range of movement of the movable member is increased, and fewer bearings are required, and a simplified actuator means is available for utilizing part of the linkage to cause the said initial movement of the movable member.

A further object of the invention is the provision of a link having fragmentary or segmental shafts that are desirably integral therewith, as set forth.

Other objects and advantages of the invention will become apparent as the specification proceeds.

With the aforesaid objects in view, the invention consists in the novel combinations and

arrangements of parts hereinafter described in their preferred embodiments, pointed out in the subjoined claims, and illustrated in the annexed drawings, wherein like parts are designated by the same reference characters throughout the several views.

In the drawings:

Figure 1 is a diagrammatic sectional view showing a device embodying the invention.

Fig. 2 is an isometric view of a link embodying the invention.

Fig. 3 is a diagrammatic view with parts in section showing a modification of the invention with a linkage in dead center position.

Fig. 4 is a similar view thereof but showing the linkage of Fig. 3 in open or collapsed position.

Fig. 5 is a sectional view taken on the line 5—5 of Fig. 3.

Fig. 6 is a fragmentary diagrammatic view showing a modification in dead center position.

Fig. 7 is a similar view of still a further modification in open position.

Fig. 8 is a fragmentary plan view showing the preferred form of the invention as applied to a molding machine or the like.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawings, therefore, are submitted merely as showing the preferred exemplification of the invention.

Referring in detail to the drawings, 10 denotes a device embodying the invention. The same may include relatively fixed and movable members 11 and 12 respectively, the member 12 being movable in a straight path, and any motor 13 movable parallel to said path and being adapted to cause reciprocation of the member 12. For transmitting power from the motor to the member 12, a toggle 14 is provided, which may include links 15 that may be identical with each other.

As shown in Fig. 2, each member 15 may consist of a plane plate of uniform thickness and 50 being of the shape of a rectangle, except that it may have segmental shafts 16 and 17 integrally projecting therefrom. Each of said shafts is in cross section less than a semicircle, and each is bounded by a section of a cylindrical surface at 18, the diameter of which is substantially equal

to the thickness of the plate. The opposite or outer sides of each segmental shaft 16 and 17 is formed by two plane surfaces 19, 20 forming an obtuse angle with each other. The surfaces 19 constitute the normal edge surfaces of the plate 15 and are at right angles to the plane thereof, and may extend continuously along the segmental shafts. The surfaces 20 are parallel to each other, and also form continuous surfaces along the ends of the link and along the segmental shafts 16, 17. Both surfaces 19 and 20 are radial to the axis of their segmental shafts, and thus the areas of both are substantially equal.

It will thus be apparent that the segmental shafts 16, 17 are actually duplicates of each other, except that in angular relation, one is at 180 degrees relative to the other. It will be further perceived that the plane surfaces 19, 20 at an end of the link may be considered as forming a generally convex surface; in fact, they may be replaced by a segment of a cylindrical surface except that the abutting pressure in dead center position would be along a line of tangency, instead of along the large area afforded by a plane surface. The latter possesses the advantage of maximum distribution of bearing pressure and is thus less subject to distortion and wear than a curved surface. Within the scope of the invention, the term convex surface denotes both. In fact, the surfaces 19, 20 are curved along their line of intersection 21 to reduce wear and distortion; such curves are also afforded at similar intersecting surfaces of the other modifications herein.

When two links 15 are placed end to end, as in Fig. 1, adjoining segmental shafts 16 and 17 form in effect a single shaft or pin which may be received in a circular collar or bearing such as 22 so that the cylindrical faces 18 are in contact with the cylindrical faces of the bearing. But due to the angularity of the surfaces 19 and 20, free radial spaces, such as sectors of a circle result which afford clearance for a relative angular movement of the shafts 16, 17 and hence of the links 15.

Any suitable bearing elements such as the yokes or collars 23 may secure the different segmental shafts 16, 17 to the members 11 and 12. Desirably the adjacent faces 24 of these members are plane for abutting contact with the surfaces 19 when the linkage is in dead center position as shown in Fig. 1. In that sense the members 11 and 12, or at least their surface portions such as 24 are herein considered as parts of the bearings, and the term bearing as here used is intended also to apply in the modifications hereinafter described.

To actuate the linkage 14, a link 25, of which the bearing element 22 may be a part, may be connected to the motor 13 at a suitable angle.

In operation, when the motor or cross head 13 moves to the right, the link 25 pulls downward on the linkage 14, collapsing the same and pulling the member 12 rightward. Downward movement of the linkage is limited by abutment of the faces at 24, and by abutment of the adjacent faces 20 with each other. While such stop action is desirable, it is not absolutely essential, since the device 13 may afford a stop. But it is essential to cut away as little metal as possible especially at the shafts 16, 17 and hence in a carefully designed device, the faces 20 will move to the limit of movement. This

observation applies to all the forms of the invention herein disclosed.

Further considering the operation, when the device 13 moves leftward, the link 25 pushes the linkage 14 upward and toward the left, causing a leftward movement of the member 12 and moving the linkage 14 to the dead center position shown in Fig. 1. As this movement proceeds, the surfaces 16, 17 roll on adjacent surfaces in the same way as if they were circular. Thus such rolling occurs on the surfaces 24 and on the adjacent surfaces 16 and 17. In other words, there is no sliding motion, hence no friction. There are no pins to shear. In dead center position, extreme power is attained, and actually the linkage 14 forms a very powerful column which is capable of exerting many hundreds of tons of compressive force, although the stress per square inch is relatively low. This feature is of substantial importance in presses and molding machines, in which wear, and abrasion rapidly occurred. To withstand the extreme stresses, the toggles used were of hardened steel and hence subject to fracture under shock.

It is thus an important advantage of the invention that the links such as 15 may be made of a low grade steel, suitably carburized to form a strong hard surface portion with a tough softer interior to take the shock.

It is important to note that while the surfaces 19 and 20 may have rolling abutting engagement within the different bearings, this is not really essential, and it is sufficient that the segmental shafts 16, 17 act as pivotal connectors. The body or link proper affords sufficient abutment area for all necessary purposes. Hence the surfaces 19, 20 may be spaced out of abutment within the different bearing elements, but ease of manufacture calls for uniform continuous surfaces 19 and 20 throughout. These observations apply also to the other forms of the invention.

In Figs. 3, 4 and 5 is shown a modified form of the invention which represents the preferred embodiment, being the one which I have found best suited in actual use in a molding machine; whereas the device 10 serves as a simplified illustration of the invention. In the device 26 are spaced relatively movable members of which 27 may be fixed and 28 movable. Interengaging these is a linkage 29 comprising the link 15 and a link 30. The latter differs from the link 15 only in its physical dimensions and in the fact that it is in only temporary engagement with the member 27, having a flat, free end portion or heel 31 engageable in a recess 32 of the member 27. Because the linkage is not connected to the member 27, it is normally inclined at an angle in its dead center position as shown, so that the link portion 31 is laterally forced into the recess 32 and cannot slip therein. In consequence, the surface 24 of the device 10 is modified to provide a surface 24a terminating at the center of the bearing 23, and a surface 24b which is recessed into the member 28 to lie at an angle so as to be at right angles to the linkage when the latter is in its dead center position. Instead of the element 25 of the device 10, a crank-like member 33 is provided which may include the bearing 22 as a part thereof. Extending through the link 30 and the members 33 which are at both sides of the toggle is a pin 34, which engages the links 35 that are pinned at 36 to a head 37 that moves in parallel relation to the path of the member 28. To facilitate outward movement of the link 30, an arm 38 rigid on the member 37 may have

cam or wiping engagement with the link 30 as the member 37 moves leftward.

In operation, Fig. 4 in plan view shows the device 26 collapsed with the member 28 retracted toward the right. In the bearing 23, the surfaces 20 and 24a are in abutment; in the bearing 22, the surfaces 20 are in abutment. The link 30 is inclined outward with its end portion beyond the recess 32 and inside or beyond the adjacent part of the member 27. Thus it is seen that the spacing between the members 27 and 28 may be reduced to be less than the length of the toggle 29 when collapsed. The element 30 is desirably in wiping or sliding contact with the inside face of the member 27 which thus serves as a guide for the free end of this element 30. An important feature of the invention is that the seat at 32 is laterally outward or beyond the bearing at 23, with the toggle of Fig. 3 being at an angle as shown.

Due to the angle of the element 35, when the member 37 moves toward the left, it causes a leftward travel of the member 28, the free end of the element 31 sliding along the member 27. The member 28 initially offers little resistance, and the inward break in the toggle at the bearing 22, with the application of power at the pin 34 permits this movement to occur. As the heel 31 moves into line with the recess 32, the resistance of the member 28 may be considered to have increased, and hence the toggle may begin to straighten out; or if the resistance of the member 28 is still low, the latter may be moved to its end position at the left substantially as in Fig. 1, and then the toggle may straighten out. As the member 37 continues its movement toward the left, the arm 38 assures that the link 30 moves outward sufficiently to be fully received in the recess 32. Then the toggle attains its dead end position as in Fig. 1. It need not be moved past dead end position, because the flat bearing surfaces assure a reliable locking irrespective of the members 35 and 37. The member 38 may be omitted if preferred.

In the dead center position, the surface 20 engages surface 24b, and surfaces 20 engage in the bearing 22, and the heel engages the wall of the recess 32. All these provide large abutment areas that are substantially in alignment with each other.

The importance of the inclined or angular position of the toggle 29 when in dead center position as in Fig. 3 will now be apparent; in fact, if the toggle were parallel to the path of the actuator 31, the operation would not be satisfactory. This is believed to be more clearly apparent by reference to Fig. 8, which is like the devices of Figs. 3 and 4, except that it shows two toggles according to an actual installation. When the actuator 31 moves to the right, the angularity of the straight toggles assures an accentuated force tending to break the toggles, and assures that the break occurs before the free end portion 31 of the link 30 is caused to leave its recess 32, and no binding occurs. In fact, the principal reason for providing the free end portion 31 is to realize in a high degree the advantage of the angularity of the straight toggle. When the actuator 31 moves toward the left, there is facilitated the movement of the member 28, then the engagement of the link 30 in the recess 32 and finally the straightening of the toggle.

In Fig. 6 is shown a modified device 39 which is intended to illustrate that one of the links such as 40 may be free of the inclined faces 20. Co-

operating with this link 40 is a recessed portion 41 in the movable member 42. The second link 43 may be like the link 30, but the inclined face 20 thereof may be at a larger angle than before. The segmental shaft 16 thereof is in rolling abutment with the plane right angle end face 44 of the link 40, and the like face 40 at the other end of the link is in rolling abutting engagement with the face of the member 42 including the recess 41 thereof. The device 39 may include the actuator means of the device 26.

In Fig. 7 is shown a modified device 45 to illustrate that no connecting bearings are needed at either the fixed nor movable members 46, 47. These may be provided with like stepped formations 48, and the links 49 may be duplicates of each other, each having segmental shafts 50 like those at 16 engaged in bearings 22 of the actuator 25. The plane right angle end faces 51 have rolling abutting engagement with the stepped formations 48 as indicated in the device 39. Retraction of the movable member 47 may be caused by a tension spring 52 or other actuator. The linkage actuator may serve to support the linkage when the latter is collapsed as shown. In Figs. 6 and 7, the surfaces at 41 and 48 afford convex abutting faces.

I claim:

1. A device including a relatively fixed first member, a reciprocable second member for delivering a power stroke, a toggle whereof one link is connected to the second member and the other link is separably engageable with the first member, actuator means for expanding and collapsing the toggle and for reciprocating the toggle to an extent less than the path of movement of the second member, the separable link being adapted to move laterally away from the first member in the collapsing position of the toggle, said actuator means causing said lateral movement of the separable link and causing the connected link to retract the second member, the actuator means causing the connected link to initially advance the second member and moving the separable link into engagement with the first member and finally causing the toggle to move substantially to dead center position, and stop means for limiting the lateral movement of the separable link to cause the toggle to assume a predetermined expanding position.

2. A device including a relatively fixed first member, a reciprocable second member for delivering a power stroke, a toggle whereof one link is connected to the second member and the other link is separably engageable with the first member, actuator means for expanding and collapsing the toggle and for reciprocating the toggle to an extent less than the path of movement of the second member, the separable link being adapted to move laterally away from the first member in the collapsing position of the toggle, said actuator means causing said lateral movement of the separable link and causing the connected link to retract the second member, the actuator means causing the connected link to initially advance the second member and moving the separable link into engagement with the first member and finally causing the toggle to move substantially to dead center position, and stop means for limiting the lateral movement of the separable link to cause the toggle to assume a predetermined expanding position, said toggle when in dead center position lying at an angle to the path of the second member so that the separable link laterally abuts the stop means.

3. In a toggle link mechanism, the combination of two spaced relatively movable members, and a linkage adapted to interengage said members, comprising a pair of links, and a bearing means interconnecting the same comprising a pair of fragmentary shafts which extend along each other and are adapted for relative angular movement about the axis of the bearing means, each of said shafts affording a fragment of a cylindrical surface and each being nonrotatably connected to its respective link, and a cylindrical collar engaging around said shafts in engagement with both of said fragmentary cylindrical surfaces, and at least one of said links having another like fragmentary shaft directly 15 pivotally abutting one of said members.

4. A device including a relatively fixed first member, a reciprocable second member for delivering a power stroke, a toggle whereof one link is connected to the second member and the other link is separably engageable with the first member, actuator means for expanding and collapsing the toggle and for reciprocating the toggle to an extent less than the path of movement of the second member, the separable link being adapted to move laterally away from the first member in the collapsing position of the toggle, said actuator means causing said lateral movement of the separable link and causing the connected link to retract the second member, the actuator means causing the connected link to initially advance the second member and moving the separable link into engagement with the first member and finally causing the toggle to move substantially to dead center position, and stop means for limiting the lateral movement of the separable link to cause the toggle to assume a predetermined expanding position, said actuator means including a power element reciprocable in generally parallel relation to the second member, a link connecting the power element to the toggle for operating the latter, and an arm on the power element for releasably engaging the separable link as the second member is being advanced to laterally move the separable link into engagement with the stop means.

5. In a toggle mechanism, the combination of two spaced relatively movable members, and a linkage interengaging said members and adapted to powerfully move the same apart in the dead center position of the linkage, a first bearing means interengaging the links of the linkage, a second bearing means engaging one of the links with a first of said members, at least one bearing means comprising shaft portions adapted for rolling engagement with each other, the said links having portions having direct rolling engagement with each other about the axis of the first bearing means, the link at the second bearing means having a portion having direct rolling engagement with said member about the axis of the second bearing means, said axes being transverse to said links, the link having engagement with the second of said members being movable into and out of engagement therewith, and actuator means connected to the last mentioned link for moving the latter into and out of said engagement and for thus causing expansion and collapse of the linkage.

6. A device including a relatively fixed first member, a reciprocable second member for delivering a power stroke, a toggle whereof one link is connected to the second member and the other link is separably engageable with the first member, actuator means for expanding and collapsing the toggle and for reciprocating the toggle

to an extent less than the path of movement of the second member, the separable link being adapted to move laterally away from the first member in the collapsing position of the toggle, said actuator means causing said lateral movement of the separable link and causing the connected link to retract the second member, the actuator means causing the connected link to initially advance the second member and moving the separable link into engagement with the first member and finally causing the toggle to move substantially to dead center position, and stop means for limiting the lateral movement of the separable link to cause the toggle to assume a predetermined expanding position, and means operated by the actuator means for releasably engaging the separable link for moving the same into engagement with the stop means.

7. A device including a first member movable along a path, mechanism comprising a toggle linkage comprising a plurality of links pivotally interconnected, one of said links being connected to the first member, the second link being movable into and out of engagement with the second member, and actuator means movable along a path parallel to that of the first member, comprising a link element connected to the second link at a point intermediate of the axis of pivotal connection and the second member, said actuator means being movable to cause the link element to pull on the linkage to break the toggle and to retract the first member, said mechanism including means to limit the breaking movement of the toggle linkage, and the actuator means being movable in an opposite direction to cause the link element to move the linkage for causing a forward movement of the first member and a swinging movement of the toggle linkage with the second link being moved into engagement with the second member and the toggle linkage being finally moved to dead center position by said link element under continued movement of the actuator means.

8. A device according to claim 7, wherein said actuator means includes a cam means for engaging the second link to urge the same into engagement with the second member in course of movement of the actuator means.

9. A device according to claim 7, wherein the toggle linkage in its dead center position extends at an angle to the path of travel of the first member, the second member having a recess for engaging and retaining the end of the second link in the dead center position.

10. A device including a toggle means comprising a toggle link consisting of a plate having at one end a surface convexed in a direction transverse to the thickness of the plate, said plate having side projections having convex surfaces forming straight continuations of the convex surface of the plate, said projections constituting fragmentary shafts whose common axis lies along the center line of the convex surfaces.

11. A device including a toggle means comprising a toggle link consisting of a plate having at one end a surface convexed in a direction transverse to the thickness of the plate, said plate having side projections having convex surfaces forming straight continuations of the convex surface of the plate, said projections constituting fragmentary shafts whose common axis lies along the center line of the convex surfaces, means having fragmentary shafts substantially complementary to those first mentioned, but one set of the shafts being cross-sectionally less than

the other so that said fragmentary shafts are adapted for pivotal movement relative to each other, and bearing elements interconnecting the adjacent shafts.

12. A device including power means comprising a relatively fixed first member, a reciprocable second power member, a toggle whereof one link is connected to the second member and the second link separably engageable with the first member, said toggle being movable substantially to dead center position between the members for moving said members apart, said toggle being collapsible with the separable link movable downward for partially underlying the first member, the power means having means for limiting the angular movement of the toggle, a power element reciprocable in a path extending in the general direction of reciprocation of the second member, and actuator means operated by the power element for operating the toggle and in cooperation with said limiting means, for reciprocating the toggle to an extent less than the path of movement of the second member while moving the second link upward and downward according to the dead center and collapsed position of the toggle, the actuator means thus causing the second member to move away from the first member to make room for the separable link whereby the toggle is engaged between the members for the power stroke of the second member.

13. A device including a power means comprising a relatively fixed first member, a reciprocable second power member, a toggle whereof one link is connected to the second member and the second link separably engageable with the first member, said toggle being movable substantially to dead center position between the members for moving said members apart, said toggle being collapsible with the separable link movable downward for partially underlying the first member, the power means having means for limiting the angular movement of the toggle, a power element reciprocable in a path extending in the general direction of reciprocation of the second member, and actuator means operated by the power element for operating the toggle and in cooperation with said limiting means, reciprocating the toggle to an extent less than the path of movement of the second member while moving the second link upward and downward according to the dead center and collapsed position of the toggle, the actuator means thus causing the second member to move away from the first member to make room for the separable link whereby the toggle is engaged between the members for the power stroke of the second member, said actuator means including a link interconnecting the power element with the separable link at a point intermediate of the ends of the latter, with the link of the actuator means being generally parallel to the connected link of the toggle in the collapsed position of the latter, and the toggle cooperating with the actuator means and the power element to limit the collapsing position of the toggle for obtaining said generally parallel position.

14. A device including a mechanism comprising a plurality of spaced relatively movable members, and a toggle therebetween comprising pivotally interengaged link members adapted for pivotal engagement with the adjacent respective relatively movable members, all of said members having interengaging means for pivotal rolling engagement between the toggle and at least one

of the relatively movable members, and between the link members, each of said means comprising a convex surface portion on one member co-operating in direct abutment with a surface portion on an adjacent member for rolling on the convex surface portion in course of operation of the toggle, each convex surface portion comprising surfaces at an obtuse angle to each other, certain of said surfaces being plane and being so located as to take the direct abutment pressure when the toggle is in dead center position.

15. A device including a relatively fixed first member, a reciprocable second member for delivering a power stroke, a toggle whereof one link is connected to the second member and the other link is separably engageable with the first member, actuator means for expanding and collapsing the toggle and for reciprocating the toggle to an extent less than the path of movement of the second member, the separable link being adapted to move laterally away from the first member in the collapsing position of the toggle, said actuator means causing said lateral movement of the separable link and causing the connected link to retract the second member, the actuator means causing the connected link to initially advance the second member and moving the separable link into engagement with the first member and finally causing the toggle to move substantially to dead center position, and stop means for limiting the lateral movement of the separable link to cause the toggle to assume a predetermined expanding position, the connected link and the second member having engagement means and the links having like engagement means therebetween, said engagement means having angularly related relatively plane abutment surface portions providing at least one convex surface for flatwise abutment at one or another of the surface portions according as the toggle is in dead center or collapsed position.

16. A device according to claim 15 wherein the connected link has fragmentary shafts at its opposite ends and the separable link has like fragmentary shafts at its adjacent end, said surface portions being extended along said fragmentary shafts, and bearings for the fragmentary shafts including a substantially half circle bearing connecting the connected link to the second member and a full circle bearing interengaging adjacent shafts of the links.

17. A device including a plurality of members movable relatively to each other, means for causing said relative movement comprising a toggle, and means for actuating the toggle, said means having bearing means, including angularly related relatively plane abutment surface portions providing at least one convex surface, for flatwise abutment at one surface portion with other surface portions being angularly spaced from each other in an expanded position of the toggle, whereby non-rolling abutting engagement is obtained in course of movement of the toggle.

18. A device including a plurality of members movable relatively to each other, a first means for causing said relative movement comprising a toggle, and means for actuating the toggle, said first means having bearing means, including angularly related relatively plane abutment surface portions providing at least one convex surface, for flatwise abutment at one surface portion with other surface portions being angularly spaced from each other in an expanded position of the toggle, whereby non-rolling abutting engagement is obtained in course of movement of

the toggle, and at least one fragmentary shaft forming an extension of at least one of said surface portions, and a bearing engaging around said shaft.

19. A device including a plurality of relatively movable head members and a toggle operatively associated with said members including a plurality of link members, one of said members having relatively plane surface portions at an angle to each other to define a convex abutment surface, and an adjacent member having an abutment surface portion cooperating therewith so that as the toggle is expanded or collapsed one or another of the relatively plane surface portions comes into engagement with said cooperating surface portion for a non-rolling abutting contact.

20. A device including a plurality of relatively movable head members and a toggle operatively associated with said members including a plurality of link members, one of said members having relatively plane surface portions at an angle to each other to define a convex abutment surface, and an adjacent member having an abutment surface portion cooperating therewith so that as the toggle is expanded or collapsed one or another of the relatively plane surface portions comes into engagement with said cooperating surface, and a fragmentary shaft on one of the members having one face portion forming an extension of the abutment surface of said member, and a bearing for said shaft mounted on the adjacent member.

21. A device including a plurality of relatively movable head members, and a toggle operatively associated therewith, including a plurality of link members, one of the latter having a fragmentary shaft not greater than a semicircle in cross

5 section, a bearing receiving and connecting said shaft to an adjoining member, the latter having a surface portion in fixed relation thereto and cooperating with the bearing for coaction with the shaft, the shaft having a surface portion in fixed relation thereto and within the bearing adapted to directly abut the first mentioned surface portion in a substantially dead center position of the toggle, at least one of said surface portions having a convex abutment surface confronting and constantly contacting the other surface portion so that different parts of the convex surface become subject to abutment pressure as movement of the toggle progresses, whereby the abutment pressure is transmitted by generally rolling contact, as distinguished from sliding contact, directly between the said surface portions.

10 22. A device including a plurality of relatively movable head members and a toggle operatively associated with said members including a plurality of link members, one of said members having a convex surface portion, and an adjacent member having an abutment surface portion cooperating therewith so that as the toggle is expanded or collapsed the convex surface portion contacts the abutment surface portion at different successive points for a rolling engagement about an axis, a coaxial fragmentary shaft on one of said members having one face portion forming an extension of the surface portion of said member, the other member having a surface portion cooperating with the surface portion of the fragmentary shaft to permit angular movement thereof, and a bearing extending around the fragmentary shaft for interconnecting the adjacent members.

15 25 30 35 PETER DE MATTIA.
